UNITED STATES PATENT OFFICE.

JULIUS DINHOFER, OF NEW YORK, N. Y.

DESIGN FOR A WATCHCASE.

Application filed February 10, 1927. Serial No. 20,671. Term of patent 3½ years.

To all whom it may concern:

Be it known that I, JULIUS DINHOFER, a citizen of the United States, residing at the city, county, and State of New York, have invented a new, original, and ornamental Design for Watchcases, of which the following is a specification, reference being had to the accompanying drawing, in which—

Figure 1 is a plan view of a watchcase showing my new design, and

Figure 2 is a side elevation of the same.

I claim:

The ornamental design for a watchcase, as shown.

JULIUS DINHOFER.
